(57) **CLAIM**

The ornamental design for an animal habitat, as shown and described.

DESCRIPTION

FIG. 1 is a front view of an animal habitat showing my novel design;

FIG. 2 is a back view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of an animal habitat of the present invention; and,

FIG. 8 is a perspective view of a first embodiment of FIG. 1.

The broken lines shown in FIG. 1 are for illustrative purposes only and forms no part of the overall claimed design.
